MOTOR CONTROLLER

Original Filed April 22, 1921

UNITED STATES PATENT OFFICE

CLARENCE T. EVANS, OF WAUWATOSA, WISCONSIN, ASSIGNOR, BY MESNE ASSIGNMENTS, TO CUTLER-HAMMER INC., OF MILWAUKEE, WISCONSIN, A CORPORATION OF DELAWARE

MOTOR CONTROLLER

Original application filed April 22, 1921, Serial No. 463,668. Divided and this application filed January 17, 1927. Serial No. 161,596.

This invention relates to improvements in controllers for electric motors.

In my Patent No. 1,479,033 issued January 1, 1924 there is disclosed a controller providing for acceleration of an electric motor subject to inductive time limit control, the arrangement being such as to insure against defeat of the accelerating operation of the controller by a high value of motor current, and the present invention relates to this general type of control.

An object of the present invention is to provide a controller of the aforesaid character wherein inductive time limit control is afforded by relays, individual relays for each of a plurality of accelerating switches being provided to afford differentiation of adjustment of the controller for different steps of acceleration.

Another object of the invention is to provide a relay affording time limit control of the character aforesaid, said relay having its contact actuating element in the magnetic field of only one winding and affording a delay by the self inductance of such winding.

Other objects and advantages of the invention will hereinafter appear.

One embodiment of the present invention is illustrated in the accompanying drawing, and the same will now be described, it being understood that the embodiment illustrated is susceptible of various modifications without departing from the scope of the appended claims.

The drawing diagrammatically illustrates a form of controller disclosed in my copending application Serial No. 463,668, filed April 22, 1921, of which the present application is a division.

Referring to the drawing, the same shows a direct current motor M which has been illustrated as comprising an armature A and a series field F. However, it is to be understood that the motor may be of other types.

The controller includes an electromagnetic main switch 1 to connect the motor across supply lines L¹ and L² through resistances R, R¹ and R², and electromagnetic accelerating switches 2, 3 and 4 to short-circuit said

resistances respectively.

The switches 1 to 4 are electrically interlocked as hereinafter more fully set forth to respond sequentially, and accelerating switches 2, 3 and 4 are respectively provided with relays 5, 6 and 7 to time the response thereof. Each of these relays as will appear affords time limit control of its respective accelerating switch and current control to some extent. However, the relays are so designed as to terminate current control when the motor current ceases to change whereby defeat of acceleration by a high value of motor current is precluded.

The relays are of like construction, each comprising a fixed contact 8 and a cooperating contact 9 which is carried by a magnetic member 10 having controlling means including windings 11 and 12 arranged in a mutually inductive relation, the former to be included in the motor circuit and the latter being short-circuited. The member 10 which forms the contact actuating element of the relay is only in the magnetic field of the short-circuited winding 12, the flux of winding 11 being confined to the circuit through the magnetic frame 13 which is separate from the magnetic frame 13^a of which member 10 forms a pivoted armature. As will be understood, when the winding 11 is subjected to a rising current it will act inductively on winding 12 to cause the latter to attract and hold its armature 10 whereas said armature will be released when the current through winding 11 ceases to rise subject, however, to a further delay by the self inductive effect of winding 12. The armature 10 of each relay carries a non-magnetic adjusting screw 14 to engage a pole of the magnetic frame to maintain a predetermined air gap between said pole and armature upon attraction of the latter and said armature is biased by a spring 15 to normally engage contact 9 with contact 8, the spring being preferably adjustable to vary the sensitiveness of response of the relay.

The winding 11 of each relay as will appear is subjected to the motor current and upon rise of the current traversing the same it acts inductively upon winding 12 whereby the latter is caused to attract its armature 10.

The armature 10 when attracted is retained in attracted position pending termination of the inductive effect of winding 11 upon winding 12 which will occur when the motor current ceases to change even though the value of the motor current may be very high. Thereupon the armature 10 will be released subject, however, to a further delay by the self inductive action of winding 12. As will later appear, the winding 11 of each relay is dependent for energization upon closure of one of the switches 1 to 3 and more particularly the one preceding the switch controlled by such relay. Hence as each relay is normally closed it should be designed in accordance with well known principles for quick response whereby it will open before the accelerating switch controlled thereby has an opportunity to close.

The power connections shown in the drawing may be traced as follows: Upon response of main switch 1 circuit is completed from line L^1 through said switch by conductor 16 through the winding 11 of relay 5, by conductor 17 to and through resistances R , R^1 and R^2 in series, by conductor 18 through the motor M to line L^2 . Upon response of accelerating switch 2 circuit may be traced from conductor 16 by conductor 19, through said accelerating switch, by conductor 20 to and through winding 11 of relay 6 to a point between resistances R and R^1 , thus affording a shunt for resistance R and the winding 11 of relay 5. Upon response of accelerating switch 3 circuit may be traced from conductor 20, by conductor 21 to and through switch 3, by conductor 22 to and through the winding 11 of relay 7 to a point between resistances R^1 and R^2 , thus affording a shunt for resistance R^1 and winding 11 of relay 6. Upon response of accelerating switch 4 circuit is completed from conductor 22, by conductor 23 to and through switch 4, by conductor 24 to conductor 18 whereby resistance R^2 is short-circuited together with the winding 11 of relay 7. Thus as above stated each of the relays is connected in circuit by the switch immediately preceding the switch controlled thereby.

The control connections are as follows: The energizing circuit of main switch 1 extends from line L^1 through a control switch 25 to and through the winding of said switch 1, by conductor 26 to line L^2 . The energizing circuit of accelerating switch 2 extends from line L^1 through auxiliary contacts 1^a of main switch 1, by conductor 27 through contacts 8 and 9 of relay 5, by conductor 28 to and through the winding of switch 2, by conductors 29 and 26 to line L^2 . The energizing circuit of accelerating switch 3 is similarly controlled by auxiliary contacts 2^a of accelerating switch 2 and the contacts of relay 6, while the energizing circuit of switch 4 is similarly controlled by auxiliary contacts 3^a

of switch 3, and contacts of relay 7. Thus as above stated, the switches 1 to 4 are interlocked to insure response thereof sequentially.

Considering the operation of the controller it will be apparent that upon closure of main switch 1 to complete the motor circuit the relay 5 will open in response to the rise in the motor current from zero value and that when the motor current ceases to change or substantially ceases to change the relay 5 will be permitted to reclose subject to a further delay by the self inductive action of its short-circuited winding 12 whereupon the first accelerating switch 2 will be energized. Thereupon relay 6 will be caused to respond, its winding 11 being now connected in series with the motor and being subjected to a current rise from zero value. On the other hand, when the winding 11 of relay 6 receives the full motor current and the motor current substantially ceases to change the armature 10 of relay 6 will be released subject to a further delay by the self inductive action of its winding 12 whereupon the second accelerating switch 3 will be energized. This will cause relay 7 to function in a manner similar to relay 6 to energize the last accelerating switch 4 subject to a time element.

What I claim as new and desire to secure by Letters Patent is:

1. The combination with an electric motor, of a resistance therefor, a switch to complete the motor circuit through said resistance, electroresponsive accelerating switches to exclude said resistance from circuit in steps, a plurality of relays respectively controlling the energizing circuits of certain of said accelerating switches, said relays each having electroresponsive control means and each having its contact actuating part in the magnetic field of one winding only and connections whereby each relay is rendered responsive to the current in the motor circuit to delay energization of its respective accelerating switch, each of said relays after response being automatically rendered effective to energize its respective accelerating switch regardless of the instantaneous value of the motor current but subject to a time delay through self inductance of the aforementioned winding of the relay.

2. The combination with an electric motor, of resistance in circuit therewith, an electroresponsive switch to exclude said resistance and control means for said switch including an electroresponsive relay responsive to current in the motor circuit to delay response of said switch and releasable to render said switch responsive, said relay being operable by the magnetic pull of a single winding, and said winding having connections whereby it produces an inductive delay in the release of said relay.

3. The combination with an electric motor,

of resistance in circuit therewith, an electro-responsive switch to exclude said resistance, and control means for said switch including an electroresponsive relay responsive to current supplied to the motor to delay response of said switch and releasable regardless of the instantaneous value of the motor current to render said switch responsive, said relay having a magnetic winding to produce a magnetic flux which alone is sufficient to operate said relay, and said winding having connections causing it to produce an inductive delay in the release of said relay.

4. The combination with an electric motor, of resistance in circuit therewith, an electro-responsive switch to exclude said resistance, and control means for said switch comprising an electroresponsive relay operable by the magnetic pull of a single winding and supplied with motor current for effecting its response to delay response of said switch, said relay being releasable regardless of the instantaneous value of the motor current to render said switch responsive but said winding having connections causing it to produce an inductive delay in the release of said relay.

5. The combination with an electric motor, of resistance in circuit therewith, an electro-responsive switch to exclude said resistance, and control means for said switch including an electroresponsive relay, said means being supplied with motor current for effecting response of said relay to delay response of said switch and said means having inductance to delay release of said relay, but said relay being releasable regardless of the instantaneous value of the motor current to effect response of said switch.

6. The combination with an electric motor, of resistance in circuit therewith, and control means for said resistance comprising windings arranged in an inductive relation, one of said windings being supplied with motor current and the other being short-circuited, said control means further comprising a contact actuating element arranged in the magnetic field of said short-circuited winding only, to be attracted by the magnetic flux of said winding alone and to be subjected to a delay in release thereof by the self-inductive action of said short-circuited winding.

7. The combination with an electric motor, of resistance in circuit therewith, and control means for said resistance comprising a short-circuited winding, a winding supplied with motor current and magnetic means placing said windings in an inductive relation and providing a magnetic circuit for said short-circuited winding separate from the magnetic circuit of the other of said windings, and a contact actuating element forming an armature in the magnetic circuit of said short-circuited winding only.

8. The combination with an electric motor, of resistance in circuit therewith, an electro-

responsive switch to exclude said resistance, and a control relay for said switch having a winding to be subjected to motor current, a short-circuited winding arranged in an inductive relation with the former winding and a contact actuating element subjected to the magnetic pull of said short circuited winding only.

In witness whereof, I have hereunto subscribed my name.
